(57) **CLAIM**

The ornamental design for a toy pistol, as shown and described.

DESCRIPTION

FIG. 1 is a front, top and right-side perspective view of the toy pistol showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and right-side perspective view thereof;

FIG. 9 is an enlarged view of area 9 in FIG. 1;

FIG. 10 is an enlarged view of area 10 in FIG. 6; and,

FIG. 11 is an enlarged view of area 11 in FIG. 7.

The evenly broken lines in the drawings depict portions of the toy pistol, which form no part of the claimed design. The dash-dot broken lines encircling the enlarged views at FIGS. 1, 6, 7, 9, 10 and 11 are shown for the purpose of illustrating the bounds of the enlargement and form no part of the claimed design.
